UNITED STATES PATENT OFFICE

CHARLES S. BARON, OF TIFFIN, OHIO

ARTICLE CONTAINER AND HINGED LID THEREFOR

Application filed September 7, 1927. Serial No. 218,071.

My invention relates to article containers generally, and specifically to display containers having each a large open mouth covered by a lid hinged securely thereto by a novel, simple, and effective means of attachment.

Display containers being intended for the display of articles of merchandise and for the introduction into a container and withdrawal therefrom of articles offered for sale, have large open mouths, and are ordinarily made of transparent material, usually glass.

A display container demands some sort of cover for protection of its contents in use.

The fragile nature of such a container and the relative size of its mouth present, in respect to providing suitable and inexpensive means for attaching to it a hinged lid, a mechanical problem which is solved by my invention.

What constitutes my invention is herein-after described in detail, and is succinctly defined in the appended claims.

In the accompanying drawing, in which my invention is illustrated in present preferred form of embodiment,

Figure I is a side elevation on a reduced scale of a container having a lid hingedly secured to it by the means of attachment comprehend by my invention.

Figure II is a top plan of the container collar, detached.

Figure III is a vertical section on an enlarged scale of the hinge connection illustrated in the preceding figures, showing so much of the container and lid as are necessary to illustrate the relationship of the several parts, one to another.

Figure IV is an exterior elevation of the subject matter of Figure III.

Referring to the numerals on the drawings, 1 indicates the body of a container which is preferably, for reasons aforesaid, made of glass, and which is provided with an integral mouth-defining ring 2. The ring is provided with an outwardly extending peripheral flange 3, defining between it and the body 1 an annular recess 4.

Fitted snugly within the walls which define the recess 4 is a flexible collar body 5,

which may be made of a strip of sheet metal. The ends of the said collar body 5 consist of loops 6 and 7 formed, preferably, by inwardly bending the ends of said strip so as to bring them into confining contact with the bottom of the recess 4. The length of a collar made from the body 5 may be varied at will so as to fit different sizes of containers by variation of the length of the loops 6 and 7 thereof. A fastening member 8 is necessary for the completion of the said strip into the form of a collar. For that purpose the member 8 is preferably made of flat metal and is on one side bifurcated by provision upon it of two adjacent legs 9 and 10, whose length is made a little greater than the width of the recess 4. On the side of the member 8 opposite the legs 9 and 10, a pair of knuckles 11 and 12 are preferably provided as part of a hinge connection with a portion of a ring 15 which is preferably confined in the skirt 16 of a lid 17 for the container. The knuckles 11 and 12 are preferably formed by flat metal projections extending from the member 8, and which, after being first inserted, respectively, through slits 19 and 20 in the skirt 16, are afterwards bent around the ring 15 so as to constitute that portion thereof about which the projections are bent into a pintle, which with the knuckles 11 and 12 complete the hinge connection aforesaid for securing the lid 17 to the container.

There is provided on the member 8, preferably between the said knuckles, a fulcrum plate 21 which is disposed substantially at right angles to the legs 9 and 10. The width of the plate 21 is such as to enable it to functionate with a wedge effect upon the legs to force them against the bottom of the recess 4, for holding the united collar body 5 and the fastening member 8 securely in place upon the container.

In order to mechanically combine the members enumerated in the last preceding sentence into operative assemblage, the member 8, hinged to the lid 17 as above specified, is secured to the collar body 5 by slipping the legs 9 and 10 into the loops 6 and 7, respectively. Then the free ends of said legs may be fulcrumed against the body 1 at its junc-

ture with the lower edge of the recess 4, and, by pressure applied to the member 8, the legs thereof are used as levers to exert strain upon the collar body 5, occasioned by the forcing of the knuckles 11 and 12 away from the flange 3 a sufficient distance to enable the plate 21 to pass the said flange. The result of said operation is to produce tension upon the collar body 5 with the effect of drawing it taut within the recess 4. After the plate 21 passes over the flange 3, the member 8 is released and the residual tension on the collar body 5 is sufficient to draw the plate 21 towards the bottom of the recess 4 underneath the flange 3. Thereupon the plate 21 serves to confine the member 8 and the collar body 5 secured thereto in position on the container to afford a stable support for hingedly securing the lid 17 to the container.

20 In case of need, the parts may be disassembled, for example, by inserting any suitable tool between the member 8 and the bottom of the recess 4. By operating the tool with lever effect against the member 8 in opposition to the force of resiliency in the collar body 5, said member may be pried away from said recess a sufficient distance to permit the plate 21 to clear the flange 3. Thereupon, the tension upon the collar body being relieved, the 25 legs 9 and 10 may be easily withdrawn from the loops 6 and 7, and all the members separated one from another. By this means the connection between the lid and a container may be made or unmade whenever occasion 30 35 may demand, thereby permitting the substitution of one container for another in case of breakage of the body of a container, for instance.

What I claim is:

40 1. The combination with a container having a mouth and a flange-defined recess about the outside of the mouth, of a collar body within said recess provided with terminal loops, a fastening member having legs engaging said loops, respectively, and a lid hinged to said member.

45 2. The combination with a container having a mouth, and a flange-defined recess about the outside of the mouth, of a collar body, a fastening member uniting the ends of said body, and a fulcrum plate on said member adapted to exert tension on the collar for holding it in place in the recess, and, when slipped under the flange, to hold the several parts together 50 55 in secure assemblage.

3. The combination with a container having a mouth, and a flange-defined recess about the outside of the mouth, of a collar body 60 within said recess provided with terminal loops, a fastening member having legs engaging said loops, respectively, and a fulcrum plate extending between said member and the bottom of said recess with wedging action on 65 65 the legs thereof adapted to exert tension on

the collar body and thereby hold it in place within said recess.

4. The combination with a container having a mouth, and a flange-defined recess about the outside of the mouth, of a collar body 70 within said recess provided with terminal loops, a member adapted to engage said loops and unite the ends of the collar body, a lid hinged to said member, and a flange-engaging piece on said member adapted to assemble 75 and disassemble the elements aforesaid at will.

5. As a new article of manufacture a fastening member for uniting a collar body to a container as specified, comprising a pair of 80 legs disposed substantially in the same plane and a fulcrum plate disposed substantially at right angles to the legs.

In testimony whereof I have hereunto set my hand.

CHARLES S. BARON.
